UNITED STATES PATENT OFFICE.

NORMAN H. BEEBE, OF WICHITA, KANSAS, AND GEORGE WILLIAM DUVALL, OF DAVENPORT, IOWA, ASSIGNEES TO LEE BROOM & DUSTER CO., OF DAVENPORT, IOWA, A CORPORATION OF IOWA.

BROOM-BANDING MACHINE.

1,103,861.

Specification of Letters Patent. Patented July 14, 1914.

Application filed January 22, 1912. Serial No. 672,692.

To all whom it may concern:

Be it known that we, NORMAN H. BEEBE and GEORGE W. DUVALL, citizens of the United States, residing at Wichita, in the county of Sedgwick and State of Kansas, and Davenport, county of Scott, and State of Iowa, respectively, have invented certain new and useful Improvements in Broom-Banding Machines, of which the following is a specification.

Our invention relates to an improvement in machines used to compress metal bands on the fiber or brush portions of brooms.

The objects sought are a simple, compact, and efficient mechanism for compressing these bands and completing the broom.

With these objects in view, our invention consists in certain novel features of construction and combinations of parts which will be hereinafter fully described and pointed out in the claim.

In the accompanying drawings:—Figure 1 is a view in front elevation showing the machine from the operator's side, Fig. 2 is a view in side elevation, Fig. 3 shows a metal band before and after compression, Fig. 4 illustrates the band around the brush or fiber of a broom before being compressed by the machine, and Fig. 5 illustrates the broom after the broom has been through the machine and the bands have been compressed.

The numeral 1 shows the main frame of the machine, and the bearing 1^a at the top is a part of this main frame.

The numeral 2 is the belt wheel made heavy to act as a balance wheel. This wheel is attached to the hub 3 of the pinion 4. Pinion 4 and its hub 3, together with the wheel 2, revolve on the stationary shaft 5. This shaft is secured to bracket 6, which in turn is attached to the main frame 1. Pinion 4 meshes with and imparts motion to the gear-wheel 7. Wheel 7 revolves freely on shaft 8. The hub of the wheel 7 is formed into one-half of a ratchet clutch, as shown. Member 9 forms the other half of the ratchet clutch. This member 9 slides longitudinally upon the shaft 8, causing the shaft to revolve through the medium of the key 10. The member 9 is provided with a circumferential groove B. The bell-crank 11 is provided with pins 12, 12, which extend into the groove B. The springs 13 (one on either

side) draw the member 9 forward to the position shown in Fig. 2. To slide the member 9 into mesh with the hub of wheel 7, a downward pressure is applied to foot-treadle 14, and the downward movement of treadle 14 is communicated to bell-crank 11 by means of the rod 15.

Connected to the forward end of the shaft 8 is an eccentric rod 18. The lower end of the rod 18 journals around a pin 19, which pin is held by the hollow box-like projection 65 made a part of cross-head 20. By means of the eccentric 16 on shaft 8, strap 17, and rod 18, a vertically reciprocating motion is imparted to the cross-head 20, which cross-head slides in grooves provided on the inner faces 70 of the guides 21 and 22. Attached to the lower end of cross-head 20 is the form 23. This form is provided with as many grooves as it is desired to press bands on the broom.

The form 24 is attached to the top of the 75 inverted U-shaped yoke 25. This yoke slides in a vertical plane on the extension 40 of the main frame 1, shown by the dotted lines, where it is retained by a plate 41. The yoke 25 is attached to the yoke-plate 80 26. Between the plate 26 and the tension plate 27 is the compression spring 28. This spring is held under any desired tension by means of the bolts 29 and 30, which have nuts 35 and 36 respectively on their lower 85 ends for that purpose. The threaded adjusting wheel 31 operates on the adjusting screw 32. This screw is provided with a head, and passes through a hole in the forward extension 40 of the main frame 90 (shown in dotted lines), where it is suspended by the head as shown by the dotted lines. It will be seen that form 24, yoke 25, spring 28, plate 27, bolts 29 and 30 are all raised and lowered vertically by means 95 of the adjusting wheel 31 without disturbing the tension of spring 28.

The operation of the machine is as follows:—The bands are placed around the broom as shown in Fig. 4. The broom is 100 then held between the forms 23 and 24 so as to bring each band in the opposed grooves of the form. The operator now presses down the treadle 14, thus sliding the members of the clutch in mesh. As the wheel 7 105 is constantly revolving, shaft 8 together with eccentric 16 will revolve, causing the rod 18, cross-head 20, and form 23 to ap-

proach form 24, thus pressing the bands tightly on the fiber, as shown in Fig. 5. An over-pressure is prevented by the spring 28. The vertical adjustment enables the machine to press the bands on large and small brooms. The operator holds the treadle down until the machine makes one revolution. He then removes his foot from the treadle, and the spring 13 disengages the clutch, thus bringing the forms to a state of rest, as illustrated in Figs. 1 and 2 of the drawings.

Having fully described our invention, what we claim as new and desire to secure 15 by Letters Patent, is:—

In a broom banding machine, the combination of a main frame, two forms between which the broom is banded, means for reciprocating one of said forms, a yoke mov- 20 ably supported and guided on an arm of the main frame, a screw depending from the said arm of the frame, two plates through

which the screw extends, one of which plates is secured to the yoke, a spring surrounding the screw and interposed between the plates, 25 a nut on the screw for raising and lowering the form carried by the yoke to adjust it with respect to the other form and the size of the broom to be made, and means independent of the nut and screw for varying 30 the tension of the spring.

In testimony whereof we affix our signatures, in the presence of two witnesses.
